UNITED STATES PATENT OFFICE.

THORVALD N. GARSON, OF NEW BRIGHTON, NEW YORK.

HOISTING DEVICE.

Application filed February 20, 1928. Serial No. 89,890.

The object of the invention is to provide a hoisting apparatus of the class in which a revoluble crane and operating mechanism therefor is combined both for power and support with a tractor, the crane elements with their driving connections also being adapted for attachment to a stationary power unit. The invention will be described more fully in connection with the accompanying drawings, in which—

Figure 1 is a side elevation of an embodiment of the invention;

Figure 2 is a side elevation and fragmentary view showing a clam shell bucket and operating devices for connection to the embodiment of Figure 1;

Figure 3 is a plan view of the device illustrated in Figure 1, the view being somewhat enlarged and the inner portion of the boom 20 being broken away to expose the drums and incidental mechanism;

Figure 4 is a sectional elevation of the revoluble mast and supporting column;

Figure 5 is a sectional front elevation of the said take-up and locking mechanism;

Figure 6 is a side elevation of the same;

Figure 7 is a diagrammatic view illustrating the spring and drum of the automatic boom rope take-up and locking mechanism;

Figure 8 is a plan view of the clutch and brake mechanism for a hoisting drum and

Figure 9 is a side elevation of the same;

Figure 10 is a plan view of the revoluble mast operating mechanism;

Figure 11 is a fragmentary view in elevation of the automatic throw-out mechanism for the mast revolving mechanism, and

Figure 12 is a front elevation of the device illustrated in Figures 1 and 3.

The device illustrated in the drawings comprises a tractor A of any suitable construction having a rear axle 1, a front axle 2 and suitable intermediate connecting members, the engine operating a sprocket wheel 3 from which power is taken to drive the elements of the hoisting mechanism.

The hoisting mechanism is carried by a frame having a three-point connection with the tractor. The frame comprises the two side longitudinal members 4, the front risers 5 and the rear risers 6, which frame members may be channel irons bolted together either directly or through the intermediary of plates such as the plates 7. The risers 5 are connected together by front plate 8, the risers 6 are connected by a rear plate (not shown),

and the two sets of risers are connected by suitable side plates such as 13. Frame members 4 at their front ends are connected to a curved hanger or bracket member 9, which has a pivotal connection at 10 with the front axle 2. The frame is hung on the rear axle through the intermediary of the risers 7, each riser having a U-bolt 12 embracing the axle 1. By the described arrangement the frame for the hoisting mechanism is given a three-point suspension upon the axles 1 and 2.

Suitable plates may be bolted upon the upper horizontal frame members so as to form a table or support for a standard 14, which standard is provided with an annular base 15, provided with apertures 15^x to receive bolts for securing the same to the said table.

The standard in the main is coniform, but it is provided with spaced cylindrical bearing portions 16. At its top the standard is adapted to receive and support an annular bearing member 17 for receiving the load of a revoluble mast 18. Secured upon the cylindrical bearing portions 16 are rings of babbitt or other anti-friction material, which may engage the inner walls of the revoluble mast.

Said anti-friction bearing surfaces may be lubricated by means of grease-cups or other suitable lubricating mediums (not shown).

At its lower end the revoluble mast 18 is formed with a projecting arm 20 to provide a pivotal support for the boom 21, the pivotal point being indicated at 22. The boom 21 is preferably constructed of two spaced channeled bars connected at their ends in any suitable manner and their rear end bolted to a plate 21^x which is apertured to receive the bolt or stud affording the pivotal connection with arm 20.

The mechanism for revolving the mast will now be described:—

Near its lower end the mast has secured thereto a bull-ring 23, the ring having inwardly projecting arms 24 which are bolted to the mast. The bull-ring is channeled to receive a drive belt or chain 25 which is driven by a pulley or sprocket 26. Pulley 26 is on a shaft 27 (Figure 10) which, below the pulley, carries a bevelled gear 28 which is in constant mesh with a bevelled gear 29 loose on shaft 30, and with a second bevelled gear 29^x loose on said shaft. A rotary clutch member 31 is keyed on shaft 30 and is provided with opposite clutch faces which are complementary to clutch faces on gears 29,

29^x. When clutch member 31 is moved to the left by lever 32, gear 29 will be operated by shaft 30 and will rotate pulley 26 in one direction, and when lever 32 is swung to 5 carry clutch member 31 into engagement with gear 29^x, the pulley 26 will be rotated in a reverse direction. In this manner the bull-ring 23 and mast 18 with boom 21 and its connecting members may be swung to the 10 right or to the left any required distance.

Undue rotation of the mast in either direction is prevented by an automatic throw-out device which comprises a trigger-lever α pivoted at α' upon an upper frame member 15 and having its upper end projecting into the path of a contact device carried by the bull-ring. When the boom is swung to such position that the contact device engages the trigger-lever, the latter will be rocked on its fulcrum a predetermined distance sufficient to throw clutch lever 31 into neutral position, the trigger-lever being suitably connected to the clutch lever as shown in Figure 11. Two trigger-levers α may be employed if desired, 20 according to the construction illustrated in Figures 10 and 11, one trigger-lever being connected to the clutch lever through cable 33, a cable 33^x being employed as the second connection. Shaft 30 is driven by reduction 25 gears 34, 34^x through a sprocket and chain connection 35 with a sprocket 36 on a shaft 37 (Figures 1 and 3), which shaft is driven through reduction gears 38 from main drive shaft 39. Drive shaft 39 carries a sprocket 35 40 connected by chain 41 with the sprocket wheel 3 from which the power is taken.

The means for raising and lowering the boom will now be described:—

At its upper end the mast is provided with 40 a bracket 18^x formed with a suitable bearing aperture for the reception of a shaft 42 upon which pulley 43 is mounted. Both the standard and the mast have central longitudinal 45 passages, and through this passage extends hoist cable 44 which is led over pulley 43 and thence to a sheave 45 at the outer end of the boom. The hoist cable thence passes over the pulley of a hook block 46, thence over a guide sheave 47 carried by the boom, the cable extending to an anchorage 48 on the mast 18. That part of the hoist cable below the mast is led over a guide-pulley 49 and is then led 50 to a drum 50 loosely mounted on a shaft 51. Drum 50 carries a gear wheel 52 in mesh with a pinion 53 loosely mounted on shaft 37. Keyed to said shaft is a sliding internal clutch member 54 which is adapted to coact with an external clutch member 55 secured to pinion 53. When the clutch members 54 55 and 55 are operatively engaged, pinion 53 will be caused to rotate with shaft 37, which is a constantly rotating shaft, and drum 50 will be operated to wind in the hoist cable 54. Shaft 51 is provided with a second drum 56, the latter carrying a gear wheel 57 engaged

by a pinion 58 loosely mounted on shaft 37. Pinion 58 carries an external clutch member 59 adapted to be engaged by an internal clutch member 60 keyed on shaft 37.

Means for operating the clutch members 70 will now be described, and inasmuch as the said means for operating the right hand clutch member is identical with that for operating the left hand clutch member, a description of the first means will suffice for 75 the two, it being illustrated in detail, Figures 8 and 9:

The internal clutch member 60 carries a channeled collar 60^x and the end of a lever 61 is seated in the channeled, the lever having a 80 lower extension 61^x, the two forming a fork. The lever is pivoted at 62 and is connected by means of link 63 with a bell crank 64, the latter being pivoted on a bracket 65 carried by one of the side plates on the frame, such as 85 13. The outer end of bell crank 64 is apertured to receive a rod 66, which rod has threaded thereon nuts 67 placed at opposite sides of the bell crank so that movement of rod 66 in reverse directions will operate the 90 bell crank in like directions and will move the internal clutch member 60 into and out of engagement with the external clutch member 59. At the outer end of the bell crank 64 is a depending extension 64^x which is pivotally connected thereto at 68^x one end of a link 68 which at its opposite end is connected at 69^x with a hand lever 69 pivoted at 70 upon a frame member. Hand lever 69 may be provided with a pawl 71 for engagement with a 95 ratchet 72, the two acting as a latch to hold the lever in various positions within the range of movement of the lever. When lever 69 is moved outwardly it will act upon bell crank 64 and lever 61 to disengage clutch members 59 and 60, thereby discontinuing the power-rotation of the appropriate drum, and when the lever is moved inwardly the 100 clutch members will be engaged to operate the drum.

When the clutch members are disengaged and power is withdrawn from the drum, the latter is automatically braked by mechanism now to be described:

To rod 66 is pivotally connected a link 73 which in turn is pivoted to the upper end of a brake-lever 74 mounted on a shaft 75 for oscillating movement relatively thereto. To the lower end of brake lever 74 is applied a spiral spring 76 which is placed under tension and is connected at 77 to the frame member 13. The spring acts to normally maintain brake lever 74 in operative or braking relation to the clutch. External clutch member 59 has applied thereto a brake band 78 which may be lined in accordance with the usual practice. One end of the brake band is strapped to shaft 75 and the other end is adjustably connected to a short arm 74^x carried 115 by the brake-lever 74, as shown in Figure 9. 120 125 130

The arrangement is such that when clutch operating lever 69 is moved inwardly to interengage the clutch members and operate the drum, brake lever 74 receives movement from rod 66 and the lever acts against the tension of spring 76 to release the brake. When, however, latch 71 is released and the clutch operating lever moved outwardly, the brake will be applied to the external clutch member and the drum operating pinion will be braked to cause, through its connection with drum gear wheel 57, a braking of the drum. The braking action is very quickly effected because of the action of spring 76, the pull of said spring hastening the manual clutch releasing movement of clutch operating lever 69.

The presence in the combination of two separate drums 50, 56 is particularly advantageous when it is desired to operate the clam shell bucket such as illustrated in Figure 2. In that case one drum will be employed to raise and lower the bucket through cable 79 and the second drum employed to act upon the closing line 80, the latter passing over a guide-pulley 81 and thence into operative connection with the closing wheel 82. Of course, in such adaptation of the device the block 46 will be removed and the closing line may pass over sheave 45 and the hoist cable be led over sheave 47 and thence over a guide-pulley 43^x to the appropriate drum.

One of the important features of the invention is the provision of automatic latching mechanism for the boom, which mechanism serves to hold the latter in any position in which it may be raised by the hoist rope and permits immediate lowering of the load to a point perpendicularly below the end of the boom in its raised position at any time. To this end there is connected to the boom at a point preferably between its longitudinal centre and its free end a latching cable 83 which is led to a drum 84 rotatably carried on bracket 18^x at the top of the mast. Drum 84 has fixed thereto a ratchet wheel 85 engaged by a pawl 86, which pawl is on a shaft 86^x suitably journaled in the said bracket 18^x. Pawl 86 is normally held in latching position by a spring 87, one end of the spring engaging a stop 88 carried by bracket 18^x and the other end engaging a contact 89^x at the lower end of the rod 89 which the spring surrounds. The tension of the spring is made adjustable by means of a nut or nuts 90 threaded on rod 89.

Rod 89 at its upper end is pivotally connected at 91 to an extension of pawl 86. The pawl-shaft 86^x has fixed thereon an operating arm 92 which may be rocked to release the pawl, a pull rope 93 being employed in the present embodiment.

Within latching drum 84 is a coiled flat spring B, one end of which is secured to the

drum at 94 and the opposite end is connected to a fixed member such as a disk 95, the latter being carried by shaft 96 upon which the latch drum revolves. A retainer 97 may be employed to overlie the latch drum and 70 guide the latching cable.

When the boom is lowered and the latch cable 83 is drawn out, the drum will be so rotated that the spring is turned in a winding direction and placed under tension. To enable downward movement of the boom it is necessary to hold the pawl 92 inactive by pawl rope 93. When the pawl rope is released further rotation of the latch drum is prevented by action thereon of the pawl, 80 and the boom is firmly held to permit lowering of the load to a desired position.

When the boom is raised the spring acts upon the latch drum to keep the latching cable taut, so that upon a reversal of movement of the hoist drum the taut cable, latched against downward movement, will hold the boom in its exact raised position, the lowering hoist cable being effective merely to lower the load. 90

The apparatus operates as follows:—

When it is desired to hoist a load, the appropriate clutch lever 69 is moved inwardly to simultaneously release the brake and interengage the clutch members such as 59 and 60. The drum pinion will then be power rotated to turn the hoist drum and wind in the hoist rope. If it is desired to hoist the load a height greater than that permitted by the position of the boom, the winding in of the hoist rope is continued until block 46 engages the end of the boom (at the wear plates C) and causes the boom to be bodily moved upwardly to the desired position. As the boom moves upwardly the spring-acting 100 latching drum maintains the latch rope 83 taut and the ratchet and pawl construction appurtenant to the latching drum will hold the latter against rotation, and thus hold the boom elevated when the rotation of the hoist drum is reversed and block 46 with its load permitted to descend. When the clam shell bucket is used, the operation will be the same as to the hoist rope, one of the drums being used as the hoisting drum and the second 110 drum being used as the operating means for the closing rope 80 (Figure 2) as will be understood without further explanation. 115

Although I prefer that the automatic latch drum 84 be placed on the mast, it can, of course, be placed on the boom and the latching cable anchored at one end to the mast. The downward movement of the boom may be limited by the length of the latching rope, which guards against dropping the boom. The upward movement of the boom may be limited by any suitable means. 125

I prefer that the hook block be of sufficient weight to overhaul the drum when its clutch is in open or neutral position, so that the 120

block may be lowered by gravity to take on a load. The same will be true with respect to the clam shell bucket.

The mast is located at approximately the centre of gravity of the tractor in order to equalize the distribution of weight and give stability to the machine as a whole.

Having described my invention what I claim and desire to secure by Letters Patent 10 is as follows:—

1. In hoisting apparatus comprising a mast, a boom and means for raising the boom, means for automatically latching the boom in any position to which it may be raised, 15 comprising a latching cable connected to the boom, a rotatable spring-actuated latching member for receiving said cable, said latch member being a drum being rotatable about a shaft and engaged by a spring spirally 20 circling said shaft, and a manually-releasable latching device for said drum.

2. In a hoisting apparatus, a boom, means for raising the boom, including a hoist rope, and means for automatically holding the 25 boom in raised position comprising a flexible connecting member and a revoluble device for winding in said flexible connection, a spiral spring carried by said device, said spring being placed under tension by said flexible connection upon lowering of the boom, and ratchet and pawl members for automatically 30

latching said revoluble device and thereby holding the boom in any position to which the latter may be raised by the hoist rope.

3. In a hoisting apparatus comprising a boom and means for raising the same, an automatic latching device for the boom comprising a flexible connecting member, a drum adapted to receive said connecting member, a flat spring having one end connected to the 40 drum and its opposite end held against movement, and releasably interlocking devices carried by the drum and a fixed member whereby the drum may be held against rotation in a given direction and also be permitted to revolve in said direction at the will of the operator.

4. In a hoisting apparatus, comprising a boom and means for raising the same, an automatic latch device for the boom comprising 50 a flexible connecting member, a drum adapted to receive said connecting member, a spiral spring having one end connected to the drum and its opposite end held against movement, a ratchet wheel carried by the drum, a pawl 55 engaging the teeth of said wheel, a pawl lever, a spring acting upon said lever to hold the pawl in operative position, and means for rocking said lever to disengage the pawl.

In testimony whereof, I have signed my 60 name to this specification.

THORVALD N. GARSON.
